UNITED STATES PATENT OFFICE.

HARVEY FELDMEIER, OF LITTLE FALLS, NEW YORK, ASSIGNOR TO D. H. BURRELL & CO., INC., OF LITTLE FALLS, NEW YORK.

CENTRIFUGAL SEPARATOR.

Application filed October 26, 1920. Serial No. 419,652.

To all whom it may concern:

Be it known that I, HARVEY FELDMEIER, a citizen of the United States, residing at Little Falls, in the county of Herkimer and State of New York, have invented a new and useful Improvement in Centrifugal Separators, of which the following is a specification.

This invention relates to centrifugal liquid or cream separators of the kind in which the separating bowl is mounted upon the upper end of a rotary spindle which is driven by gearing connecting the spindle with an operating crank shaft. The invention relates more particularly to improvements in the construction of the hollow frame of the machine in which the drive gearing for the bowl is housed and on which the bowl is mounted.

One object of the invention is to produce an efficient and desirable centrifugal separator in which the hollow frame of the machine is constructed so as to reduce to the minimum the number, weight and size of parts and to lessen the labor and expense incident to the manufacture and assembling of the machine. Another object is to construct the frame with the joint between the separable parts of the gear case located so as to enable the bowl drive gearing and bearings to be splash lubricated without necessitating a packed joint for the case. Other objects are to simplify and improve the construction of centrifugal separators in the other respects hereinafter described and set forth in the claims.

In the accompanying drawings:

Fig. 1 is a sectional elevation of a centrifugal separating machine embodying the invention.

Fig. 2 is a sectional elevation thereof on line 2—2, Fig. 1.

Fig. 3 is a bottom plan view of the top member of the frame.

Fig. 4 is a sectional plan view of the machine on line 4—4, Fig. 1.

Fig. 5 is a plan view of the body or lower part of the frame or casing.

A represents the bowl of a centrifugal cream separator, and B the upright spindle on the upper end of which the bowl is supported and which is rotated by drive mechanism preferably comprising a hand operated crank shaft C on which is secured a gear

wheel D meshing with a pinion E on a horizontal intermediate shaft F which is provided with a spiral gear G meshing with a spiral pinion or worm H on the bowl spindle.

The separator bowl is preferably constructed as hereinafter described.

The bowl and its drive mechanism are mounted on a supporting frame which is preferably constructed as follows: This frame comprises an upright, hollow body 10 or lower portion 10 which is preferably substantially cylindrical in shape, and a separate-piece top 11. The body 10 is usually mounted on a stand or base (not shown) so as to support the bowl and operating mechanism at the desired elevation, and the lower end of the body 10 is suitably constructed for securing it on the base. Preferably the body is provided at its lower end with the usual horizontal, rectangular flange 12 having an upstanding rim 13 and forming a drip pan, and is provided between its ends with a horizontal partition 14 forming an upper chamber or gear case 15 in which the drive gearing for the bowl spindle is housed, and which is adapted to contain oil for lubricating the gearing and bearings.

The body 10 and top 11 are separable at a horizontal circular joint formed by complementary circular parts on the upper end of the hollow body and on the under side of the top 11. As shown, the top 11 is provided with a depending circular flange 16 adapted to fit in the circular rim of the body and with a horizontal shoulder 17 adapted to rest on the rim of the body. The top is removably secured on the body, preferably by two screws 18 inserted through holes in the top into threaded holes 19 in lugs 20 in the body 10. The bowl spindle B is journaled in upper and lower bearings of the usual or any suitable kind supported respectively by the top 11 and in the hollow body 10. The lower bearing 21 shown, is a ball bearing seated in a socket 22 in the horizontal partition 14 of the body, while the upper bearing consists of the usual self centering bushing 23 in which the spindle turns, and which is yieldingly centered in an opening 24 in the top 11 by suitable springs surrounding the bushing. A cap 25 soldered or otherwise suitably secured to the bushing, and loosely secured on a flange

around the opening 24, supports the bushing loosely in the opening but permits the desired lateral play of the bushing. This cap also helps to prevent slop or liquid from 5 going down into the gear case. A collar 25^a secured on the spindle below the bushing 23, holds the spindle in the frame when the bowl is removed, otherwise the spindle would come out when removing the bowl, 10 which would be inconvenient on account of the oil that is on the spindle. The cap 25 prevents the bearing itself from being lifted out by the collar when the bowl is lifted, which tends to carry the spindle with it by 15 friction.

The top 11 is provided on its upper side with a circular flange or seat 26 concentric with the opening 24 for the bowl spindle but eccentric with relation to the circular 20 joint between the top 11 and the body 10. The bottom receiving pan for the separated liquid is seated and confined in this seat 26 so that the tinware or skim-milk and cream receiving pans 27 and 28 and the bowl casing 29 which encloses the separating bowl, 25 and which are seated one upon the other, are thus disposed eccentrically above the hollow cylindrical body portion of the frame. The eccentricity is only sufficient to enable the 30 bowl spindle with its bearings and worm to be located within the hollow frame in proper relation to the spiral gear wheel G on the intermediate shaft, thus enabling the frame to be made with a minimum amount of 35 metal.

The circular joint between the body 10 and top 11 and the circular seat 26 for the tinware can be readily machined to size by turning, and the joint between the body and 40 top is disposed well above the bearings for the intermediate shaft F and above the level of the oil in the gear case. It is therefore not necessary to pack this joint in order to prevent the oil from working out of the gear 45 case through the joint. The construction described also provides for splash lubrication of all of the bearings, except those for the crank shaft C, by oil in the bottom of the gear case. The oil can be introduced into 50 the gear case through any suitable filling opening or device 30. In order to ensure more perfect lubrication of the upper bearing for the bowl spindle by oil thrown off from the spiral gear G, the top 11 is formed 55 so as to provide on its under side a cavity 31 which converges upwardly to the bearing 23 which projects down through the opening 24. This construction obviates the necessity for a separate oiling device for the 60 upper bearing 23.

The intermediate shaft F is preferably, as shown, journaled in bushings 32 which are removably secured, as by set screws 33, in holes extending through the walls and the 65 lugs 20 at the opposite sides of the hollow

body 10. The holes for the bushings are preferably large enough for the passage of the pinion E on the outer end of the shaft F, so that when the bushings are released they and the shaft can be inserted and removed endwise through the bushing holes. The spiral gear wheel G is loose on the shaft F and is caused to turn therewith when the shaft is turned in one direction while being free to run when the shaft is stopped, by 70 means of a suitable ratchet device preferably consisting of a pin 34 arranged to slide freely endwise in a transverse hole in the shaft and extending into a scroll shaped recess 35 with an abrupt shoulder 36 in the hub of the 75 spiral gear. This construction forms an exceedingly simple ratchet connection and the ratchet pin 34 also serves to hold the gear wheel G from endwise movement on the shaft F, since the hub of the wheel is confined between the ratchet pin and one of the bearing bushings 32. After loosening the bushings the gear wheel G can be moved endwise on the shaft to permit the removal of the ratchet pin. The shaft can then be 80 withdrawn from the wheel and the latter removed from the gear casing. These parts are assembled by a reversal of this procedure.

The crank shaft C is suitably journaled on bearing standards 37 which are preferably formed integrally with and extend upwardly from the top 11.

The separator bowl A shown comprises a circular bottom 40 provided with an integral, upwardly extending, central hub 41, and an inverted, cup-shaped, open bottomed shell 42 which is clamped tightly on the bowl bottom by a nut 43 which is screwed on the threaded upper end of the central hub 41 and bears against the top of the shell. 100 The nut preferably extends down through a central hole in the top of the shell and is hollow, forming in effect, a hollow upper extension of the bowl hub 41, and has one or more lateral holes 44 through which the liquid to be separated enters the bowl. Preferably, the lower end of the shell fits around the cylindrical periphery of the bowl bottom above an outwardly extending flange thereon, and a tight joint is made by a suitable gasket or packing ring 45 which is confined in a peripheral groove in the bowl bottom. The upper portion of the periphery of the bottom is reduced in diameter to form an annular milk channel 46 between the same 105 and the surrounding wall of the bowl shell. The whole milk or liquid to be separated is fed into the bowl through the hollow nut 43 and passes therefrom into the upper portion 110 of the bowl. The skim-milk or heavier liquid is discharged from the bottom of the bowl through the annular channel 46 and exit passages 47 leading inwardly therefrom through the bowl bottom into a central discharge throat 48 formed by an annular 115

flange 49 depending from the bottom of the bowl. Any desired number of the exit passages 47 can be used.

50 represents the exit hole for the cream 5 or lighter liquid. This hole extends through the bottom of the bowl near its center into the throat 48 and is preferably made eccentrically in a screw plug which can be turned for adjusting the exit hole relatively to the 10 axis of the bowl, in a well known manner. The cream flows from this exit hole down the inner surface of the throat flange 49 and escapes through a hole 51 in the side thereof, the cream being prevented from mixing with 15 the milk in the throat 48 by an internal U-shaped rib 52 on the flange 49 which forms a flow channel for the cream.

The separator bowl can be removably secured on the spindle to turn therewith in 20 any suitable manner, for instance by the usual flat sided plug 53 secured in the hollow hub of the bowl and engaging a flat side on the upper end of the spindle which fits into the hub. 54 indicates the usual 25 separator blades in the bowl.

I claim as my invention:—

1. In a centrifugal separating machine, a bowl supporting frame comprising a hollow body and a top removably secured thereon 30 and forming a support for a receptacle for separated liquid, the joint between said top and body being circular and said top having a circular seat for said receptacle eccentric to said circular joint.

35 2. In a centrifugal separating machine, a bowl supporting frame comprising a hollow body and a top removably secured thereon and forming a support for a receptacle for separated liquid, said top having on its 40 under side a circular joint flange which fits the circular upper end of the hollow body, and on its upper side a circular seat eccentric to said joint flange for holding a receptacle in place on said top.

45 3. In a centrifugal separating machine, a bowl supporting frame comprising a hollow body and a top removably secured thereon, said hollow body forming an oil receptacle, a bowl spindle extending through a hole in 50 said top into said hollow body, and drive mechanism for said spindle including a shaft journaled in said body and connected to said spindle by gearing housed in said hollow body, the joint between said frame 55 top and body being located above the bearings for said shaft.

60 4. In a centrifugal separating machine, a bowl supporting frame comprising a hollow body and a top removably secured thereon, said hollow body forming an oil receptacle, a bowl spindle extending through a hole in 65 said top into said hollow body, a bearing for said spindle located in said hole in the top, and drive mechanism for said spindle including a wheel in said oil receptacle and

adapted to dip into oil therein, said top having in its under side a cavity leading to said hole for directing oil thrown off from said wheel to said spindle bearing.

5. In a centrifugal separating machine, a 70 bowl supporting frame comprising a hollow body and a top removably secured thereon, said hollow body forming an oil receptacle, a bowl spindle extending through a hole in said top into said hollow body, a bearing 75 for said spindle located in said hole in the top, a cap secured to said bearing and attached to said top over said hole for covering the hole and loosely retaining the bearing in the hole, and a collar on said spindle 80 adapted to engage said bearing to prevent the spindle from being pulled out of the bearing.

6. In a centrifugal separating machine, the combination with a separating bowl, and 85 a receptacle located below the bowl for receiving separated liquid from the bowl, of a bowl-supporting frame comprising a hollow body and a top removably secured on the body and forming a support for said 90 receptacle, the joint between said top and body being circular, and said top having a circular seat for said receptacles, which seat is eccentric to said circular joint.

7. In a centrifugal liquid separating machine, the combination with a separating bowl, drive gearing for the bowl, and a receptacle arranged concentrically with the bowl for receiving separated liquid from the bowl, of a bowl-supporting frame comprising 100 a hollow body in which said drive gearing is housed, and a top removably secured on said body and supporting said receptacle, the joint between said top and body being formed by circular parts of the top and body, and said top having a circular seat for said receptacle which seat is eccentric to 105 said circular joint parts.

8. In a centrifugal liquid separating machine, the combination with a separating 110 bowl, drive gearing for the bowl, and a receptacle arranged concentrically with the bowl for receiving separated liquid from the bowl, of a bowl-supporting frame comprising a hollow body in which said drive gearing is housed, and a top removably secured on said body and supporting said receptacle, said hollow body having a circular upper end through which said drive gearing is removable, and said top having a circular under part closing the upper end of said body and having at its upper side a circular seat for said receptacle, which seat is eccentric to 115 said circular under part.

Witness my hand this 22d day of October, 125
1920.

HARVEY FELDMEIER.
